Specification for Design.

Patented Apr. 3, 1917.

Application filed January 16, 1917. Serial No. 142,770. Term of patent 3½ years.

To all whom it may concern:

Be it known that I, HOMER W. CASE, a citizen of the United States, residing at Pittsburgh, in the county of Allegheny and State of Pennsylvania, have invented a new, original, and ornamental Design for Velocipedes for the Use of Children, of which the following is a specification.

Referring to the accompanying drawing, forming a portion of this specification:

The figure is a perspective view of a ve-

locipede for the use of children, showing my new design.

I claim:

The ornamental design for a velocipede for the use of children, as shown.

In testimony whereof I affix my signature in the presence of two witnesses.

HOMER W. CASE.

Witnesses:

JENNIE JONES,

R. CLEMENT WEBER.
